UNITED STATES PATENT OFFICE.

KEMPSTER B. MILLER, OF WILKINSBURG, PENNSYLVANIA.

TELEPHONE-EXCHANGE SYSTEM.

SPECIFICATION forming part of Letters Patent No. 561,335, dated June 2, 1896.

Application filed February 18, 1896. Serial No. 579,795. (No model.)

To all whom it may concern:

Be it known that I, KEMPSTER B. MILLER, a citizen of the United States, residing at Wilkinsburg, in the county of Allegheny and State 5 of Pennsylvania, have invented a new and useful Improvement in Telephone-Exchange Systems, of which the following is a specification.

My invention relates to what are known as 10 "divided-board exchange systems," and has for its object a construction of less complexity than those in use at present, which will nevertheless give quicker and more reliable service. In order to attain this object, I terminate the subscribers' lines in spring-jacks 15 arranged on divided boards. Connected to each line is an annunciator, also on the board. This annunciator not only serves to indicate calls, but also, after connections have been 20 made, as a clearing-out signal.

I provide each board with a number of connecting-plugs arranged in two sets, each set intended to be manipulated by a different operator. These plugs form the terminals of 25 trunk-lines extending between the boards. The plugs of the first set at each board which are to be manipulated by an operator, whom I shall designate the "A" operator, are to be used only to answer calls. The trunk-lines 30 from the individual plugs of the first or "A" operator's set at each board are distributed among all the boards, where they terminate in plugs of the second sets.

The second set of plugs at each board is 35 under the control of an operator, whom I shall designate as "B" operator. The "B" operator at each board is charged only with the duty of completing the connections which have been initiated by the "A" operator at her own 40 or another board, and each "B" operator, therefore, has before her in the second set of plugs one or more trunk-terminals from each "A" operator. Thus the "A" and the "B" operator at any board are each able to reach 45 and control the entire number of jacks on that board; but so far as the plugs are concerned each operator has to attend to those of her own set only.

In order that the greatest possible speed may 50 be attained in their respective duties, I provide the "A" operator with special means for listening in and for restoring the annuncia-

tors, adapted to be governed by the partial insertion or withdrawal of her plugs, and for the "B" operator special means for listening in, operated by simply grasping and slightly moving the plug with which she is to complete the connection. In addition I provide a signaling-circuit for each trunk-line, containing mutual signals for both operators. 55 These signals are directly in the circuit, together with a generator, and this circuit is directly controlled by the manipulation of the respective operators' plugs, without any intermediate apparatus and without the insertion of relays or subcircuits. 60

The means I prefer to use for restoring the annunciations and connecting the "A" operator's telephones by the insertion or withdrawal of their plugs consist of contact-springs connected to the restoring-coils and to the "A" operator's telephones, respectively, lying adjacent to the line-springs and alternate annular depressions and enlargements on the plugs so located as to interconnect the springs 70 momentarily during their insertion in or withdrawal from a jack. In practical operation each "A" operator is to be provided with a "dummy" plug held in the left hand and provided with a proper surface to operate these 75 springs. A call being received, her telephone is connected to the line and the annunciator restored by the insertion of the dummy plug. She ascertains the number desired and selects the terminal plug of the trunk-line leading to 80 the board (whether her own or another's) upon which the desired subscriber's line terminates. As she removes this plug from its seat and inserts it in place of the dummy plug, the signaling-circuit appropriate to the selected plug is automatically energized. As 85 this trunk-line terminates at the board in which the called-subscriber's line terminates in a "B" operator's set the "B" operator, noticing the signal, has only to grasp the corresponding terminal plug and tilt it slightly 90 to connect her telephone through the trunk-line to the calling-subscriber's line and in her turn ascertain the number required, when nothing remains but to lift the plug she has 95 already grasped, insert it in the proper jack, and depress the calling-generator key. The act of lifting her plug from its seat changes the 100 resistance of the trunk-line signaling-circuit

and operates the "A" operator's signal, thus informing her that the desired connection is complete.

The "B" operator's plugs will, of course, fit in the spring-jack of every line, but unlike the "A" operator's plugs they lack the projection necessary to connect the operator's telephone to line. They are provided, however, with the necessary projection to complete the annunciator-restoring circuits.

When the subscribers shall have rung off, the simple withdrawal of the plugs finally restores the annunciators, and their replacement in their seats finally deenergizes the signaling-circuit. If, however, one plug only is replaced, the corresponding signal only is actuated.

My invention is also equally applicable to small exchanges requiring but one board and one set of operators. In this case no dummy plug is required for ascertaining the number of the line desired, as the operator may insert the answering-plug of any pair not in use in the jack of the calling subscriber and ascertain the number wanted either by the use of the plug and spring-jack, already referred to in connection with the "A" operator's sets in the divided-board system, or she may be provided with plug-seat switches like those forming the "B" operator's means of listening in in the divided-board exchange. In a single-board system of this kind the operator is therefore provided with a number of pairs of plugs and with either one of the two means for listening in described in connection with the divided-board exchange.

In carrying out my invention I employ detailed constructions of the various parts, which will be fully described hereinafter.

My invention is illustrated in the accompanying drawings, in which—

Figure 1 is a diagrammatic view of the central-office apparatus and circuits of an exchange having three divided boards, the circuits and mechanism pertaining to signaling between the operators being omitted. Fig. 2 is a diagram showing the circuits and apparatus of a line both at the subscriber's station and at central. Fig. 3 is a detail view of an answering-plug and line spring-jack. Fig. 4 shows a calling-plug, and Fig. 5 is a dummy plug. Fig. 6 shows the apparatus and circuits associated with the calling-plugs, and Fig. 7 shows a trunk-line signaling-circuit.

In Fig. 1 are shown three divided boards 1, 2, and 3, each containing, say, three hundred spring-jacks and their corresponding annunciators. Each of these jacks forms a terminal for a subscriber's line. The subscribers' lines are grouped according to greatest convenience, and each terminates in one jack only. Below each board are shown two sets of plugs, the answering or "A" operator's plugs PA and the calling or "B" operator's plugs PB. One "A" operator's plug (marked 1) at board 1 is shown connected by the trunk-line T T' with a "B" operator's

plug at board 1. Another "A" operator's plug (marked 2) at board 1 is connected by a similar trunk-line to a "B" operator's plug at board 2, and still another "A" operator's plug (marked 3) at board 1 is connected to a "B" operator's plug at board 3. In like manner each "A" operator is provided with a set of answering-plugs, forming the terminals of trunk-lines, each of which runs to a calling-plug in some one "B" operator's set, so that each "A" operator is connected by a separate trunk-line with each "B" operator.

I have hereinafter termed the collection of trunk-lines running from any "A" operator's set of plugs a "set" of trunk-lines. It will now be seen that each set of trunk-lines centers in some one "A" operator's plugs, and from there the separate lines radiate in a fan-like arrangement, each running to a plug at some "B" operator's set.

For convenience and simplicity of illustration but one trunk-line is shown from each "A" operator to each "B" operator; but it will readily be understood that in practice several will be needed.

Each spring-jack J (see Figs. 2 and 3) is composed of two line-springs *a* and *b* and two auxiliary springs *c* and *d*, all normally insulated from each other and mounted, as shown, on insulating-strips *w*, or in any other suitable manner. The springs *a* and *b* of each jack are connected, respectively, to the two limbs *L* and *L'* of the line, as shown in Fig. 2. All the springs *c* of each board are connected by wire 5 to one side of the telephone *t* belonging to the "A" operator at that board, while all the springs *d* are connected by wire 6 to the other side of the same telephone.

As all the springs *c* at each board are permanently electrically united, and likewise all the springs *d*, it is advisable in practice to form them by laterally slotting a strip of brass corresponding in length to the length of a row of jacks, thus forming teeth like those of a comb. These teeth, which form the springs *c* and *d*, are so spaced as to overlie the line-springs of the separate jacks of a row.

The "A" operator's plug PA consists of two cylindrical contact-pieces *e* and *f*, mounted in any well-known manner in a handle *g* of insulating material. The contact *e* is substantially of the form shown, and consists of a ball-tip *i* and a neck *h* of reduced diameter. The contact *f* has an annular depression *k*, so placed as to leave a portion *k'* of greater diameter between it and the neck *h* of the contact *e*. These enlargements and depressions are so spaced longitudinally with respect to the plug that when the plug is partially inserted in the jack J the line-spring *a* is pressed by the ball-tip *i* into contact with the auxiliary spring *c*, and at the same time line-spring *b* is pressed by the enlargement *k'* into contact with the auxiliary spring *d*, thereby connecting the "A" operator's telephone with the line. On pushing the plug

home, however, springs *a* and *b* fall into the depressions *h* and *k*, respectively, thus breaking their contacts with springs *c* and *d*, respectively, and disconnecting the "A" operator's telephone.

- The combined calling and clearing-out annunciators are of any of the well-known self-restoring types and are each provided with an operating-coil *m* and a restoring-coil *n*.
- 10 The coil *m* is of high resistance and impedance and is connected on one side to the limb *L* of the line-wire and on the other side to ground at *G*. One side of the coil *n* is connected by wire 3 to the spring *b* of the spring-jack to which the particular annunciator belongs, while the other side is connected by the wires 4 and 6 with the auxiliary spring *d* of the same jack. The wire 4 contains a battery *B'* or other source of current.
- 15 20 The annunciator is operated by calling-current coming from the generator at the subscriber's station over the limb *L'* of the line through the coil *m* and to ground.

When an operator inserts a plug in a jack for making a connection, spring *b* is pressed against spring *d* of that jack by the larger portion of the plug, thus completing the local circuit through coil *n* and battery *B'* and restoring the annunciator. When the plug is 25 pushed entirely in, however, contact between springs *b* and *d* is broken, as before described, and the annunciator is left ready to serve as a clearing-out signal. After it has been so operated by the subscriber's ringing off the 30 35 simple withdrawal of the plug by the operator momentarily connects springs *b* and *d*, and the coil *n* is again energized to finally restore the signal.

In addition to the plugs *PA* each "A" operator is provided with a single plug *PX*, which I have termed a "dummy" plug, and which is preferably made entirely of insulating material, having no circuit connections whatever. This plug is of such a size that 40 45 50 when inserted in a jack it presses springs *a* and *b* into contact with springs *c* and *d*, respectively, just as is done by the larger portions of the plugs *PA*. It is carried by the "A" operator in her left hand, and is used 55 60 65 in a manner hereinafter described.

The "B" operator's plugs *PB*, Fig. 4, differ from those of the "A" operator in that the enlarged ball-tip *i* is omitted, thus leaving the whole tip of the same diameter as the neck *h* on the "A" operator's plug. Thus the "B" operator's plug when inserted in or withdrawn from a jack will restore the annunciator-shutter by closing spring *b* against spring *d*, but will not connect the "A" operator's telephone with the line, as would be the case were the tip of the plug large enough to press spring *a* against spring *c*. The "B" operator's plug is also fitted with a metallic heel *u*, which enables the "A" and "B" operators 65 70 75 to readily distinguish their own plugs when inserted in jacks on the same board. The

real function of this heel will, however, be referred to later.

The "B" operator's plugs rest in sockets provided with three contact-springs *q*, *r*, and *s*, Fig. 6, each insulated from the others and so fastened together by insulating material as to move in unison. In the path of the springs *q* and *r* are placed two contacts *q'* and *r'*, with which these springs are normally out 70 75 of engagement. A forward tilting of the plug *PB* while it rests in its socket presses the springs *q* and *r* into contact with their respective pins *q'* and *r'*. The springs *q* and *r* are permanently connected to the two sides, 80 respectively, of the trunk-line of which their particular plug *PB* forms a terminal, while the contact-pins *q'* and *r'* form the terminals of the "B" operator's telephone - circuit. Consequently a "B" operator in order to connect her telephone to any trunk-line has only to tilt the plug of that line toward her without removing it from its socket. A knob *Q* is provided on the spring *s*, so that in case the "B" operator wishes to listen in after her 85 90 95 plug has been removed from its socket she may do so by pulling forward on the knob, thus closing the pairs of contacts *q'q* and *rr'*. The "B" operators are also provided with calling-keys *K*, one for each plug. Each key when depressed disconnects the "B" operator's plug from the rest of the trunk-line and at the same time connects its terminals with the calling-generator "B" in a well-known manner.

In order that appropriate signals may be automatically transmitted between the two operators at both ends of each trunk-line, I provide a separate signal-circuit *S*, Figs. 6 and 7, for each trunk-line, the signals in which 105 are controlled by contacts in connection with the plug-seats of the trunk-line plugs. The sockets in which the "A" operator's plugs normally rest are each provided with two contact-springs *o* and *p*, which are held apart by 110 the plug while in its seat, but which make contact with each other as soon as it is withdrawn therefrom. These springs control the continuity of the signal-circuit *S*, of which they form a part.

The spring *s*, already referred to as being a part of the "B" operator's plug-seat mechanism, is connected to the signal-wire *S* belonging to its particular trunk-line and the metallic portion *v* of the plug-seat is grounded. 120 Thus when a "B" operator's plug is in its seat the signal-line is closed to ground through the spring *s*, metallic heel *u*, and piece *v*. The contacts *s* and *v* are permanently connected by a moderately-large resistance *R*, so 125 that the signal-circuit is never entirely broken at the "B" operator's end. The removal of the plug *PB* simply introduces the resistance *R* into the circuit.

W is a low-resistance signal in circuit at the 130 "A" operator's end of the signal-line, and *X* is a high-resistance signal in circuit at the "B"

operator's end. The two signals W and X are so adjusted to the strength of the battery Bs that W will be excited only when the resistance R is short-circuited, while X is made so sensitive that it will be operated when the contacts o p are closed, whether or not the resistance R is in circuit.

When the "A" operator removes a plug PA from its socket, springs o and p of that plug's seat make contact, thus closing the signal-circuit and displaying both signals. The signal X thus informs the corresponding "B" operator that her attention is desired on this trunk line. When she in turn removes her plug, the connection between s and v is broken and the resistance R thereby introduced into the signal-circuit, thus diminishing the amount of current flowing from battery Bs. The current now flowing is insufficient to keep signal W displayed, and it becomes deenergized, thus informing the "A" operator that the "B" operator has removed her plug for making the desired connection. If now on disconnecting the two lines the "B" operator replaces her plug in its socket before the "A" operator, signal W is displayed, informing the "A" operator of the fact that the trunk-line is disconnected at the other end. Should the "A" operator replace her plug first, the "B" operator is informed of the fact by the deenergization of her signal X, owing to the break in the circuit between springs o and p. Thus we see that the condition of signal X at plug PB depends on the open or closed condition of the contacts o p at plug PA, while the condition of signal W at plug PA depends on whether the resistance R at plug PB is in or out of circuit.

The operation of my system is as follows: A subscriber desiring a connection operates his generator in the usual way, thus throwing down the annunciator A belonging to his line. The "A" operator at the board at which the line terminates—for instance, at board 1—seeing the signal at once thrusts her dummy plug in the corresponding spring-jack. This connects her telephone tA in the line-circuit and at the same time restores the line-annunciator in a manner already described. She ascertains the number of the subscriber wanted, which we will suppose is No. 620. She knows that line No. 620 terminates on board 3, so she picks up one of her plugs marked 3, which, as we have seen, is connected with a "B" operator's plug at board 3, and inserts it in the calling-subscriber's line in place of the dummy plug. The lifting of this "A" operator's plug from its seat allows springs o p of that seat to come into contact, thus exciting both signals W and X. The "B" operator seeing the signal X excited grasps the corresponding plug PB and tilts it in its socket, thus connecting her telephone in circuit with the trunk-line and with the calling subscriber. There are now two ways in which the "B" operator can learn the number desired. The first of these is for the calling subscriber to repeat the

number, in which case the circuit over which the voice-currents travel is from subscriber's station over limb L of line, spring a, tip e of "A" 70 operator's plug, limb T, trunk-line, contacts q q', "B" operator's telephone, contacts r r', limb T' of trunk-line, sleeve f of "A" operator's plug, spring b, and back over limb L' of the line to the subscriber's station. The second way is for the "A" operator to repeat the number, in which case she only partially inserts her plug PA, so that springs a and b contact with springs c and d, respectively. In this case the talking-circuit is traced from the 80 "A" operator's telephone over wire 5, spring c, spring a, tip e of plug PB, limb T of trunk-line, contacts q q', "B" operator's telephone, contacts r r', limb T' of trunk-line, sleeve f of plug PA, spring b, spring d, and wire 6 back 85 to telephone tA. The "B" operator having received the order has only to raise the plug PB, already grasped, and insert it in the spring-jack of the desired subscriber, in this case subscriber No. 620. She then presses the calling-key K, belonging to the plug used, and sends calling-current to ring up subscriber No. 620 in any well-known manner. If at any time while two lines are thus connected for conversation the "A" operator wishes to listen in, she does so by simply withdrawing her plug part way when her telephone is bridged across the line, as already described. In like manner the "B" operator may bridge her telephone into the circuit by pulling forward 90 on the knob Q.

When the conversation between the subscribers has been completed, either may ring off by operating his generator in the same manner as for calling. The clearing-out current passes to ground through the annunciators of both connected subscribers, thus throwing them down as clearing-out signals at both the "A" and "B" operator's boards. Each operator on seeing the signal withdraws her plug and replaces it in its normal resting-socket. As an additional safeguard to prevent the lines being left connected at one of the boards the plug which is first replaced in its socket automatically actuates the trunk-line signal at the other board, thus insuring the prompt attention of the operator at that board.

In some cases it may be advisable for the annunciator of the calling subscriber only to be used as a clearing-out annunciator. The only change needed to bring about this result is to omit the depression k on the "B" operator's plug, thus leaving them of the general contour shown by dotted lines in Fig. 4. This change would cause the springs b and d of the called-subscriber's jack to remain in contact as long as a plug PB remained inserted therein. This would keep the local circuit through the restoring-coil n of the annunciator closed 120 and prevent the actuation of the annunciator by any clearing-out currents coming over the line from either subscriber's station. As the calling-subscriber's line is always connected

up by an "A" operator the clearing-out signal would in this case attract the attention of the "A" operator only. Seeing it, she would withdraw her plug and replace it in its socket, 5 which would automatically open springs *o p* of the trunk-line signal-circuit and effect the signal X, thus notifying the "B" operator that disconnection was desired.

Two forms of single-board systems readily 10 suggest themselves to those skilled in the art and clearly lie within the scope of my invention. In the first of these the spring-jacks and answering-plugs are identically the same as those already described, while the calling-plugs are similar to those represented by the 15 dotted lines in Fig. 4. The plug-seat mechanism of both plugs is of course omitted. The operator on receiving a call inserts one of the 20 answering-plugs part way in the jack of the calling-line and inquires the number wanted, on receiving which number she pushes the 25 answering-plug home and inserts the other plug of the pair in the jack of the called subscriber, when she has only to press the calling-key belonging to the pair of plugs used to 30 operate the called-subscriber's bell. The insertion of the answering-plug restores the annunciator of the calling-line, thus enabling it to be used as a clearing-out signal. After it 35 has been so actuated the withdrawal of the answering-plug again automatically restores it, leaving it ready to indicate subsequent calls. The insertion of the calling-plug in the jack of the called subscriber energizes the 40 restoring-coil, thus holding it against actuation by clearing-out currents..

In the second arrangement of single-board systems the operator connects her telephone with the line by the plug-seat mechanism 45 shown in Fig. 6. The spring *c* is omitted from the spring-jacks and the ball-tip *i* from the answering-plug. In this case an operator on receiving a call inserts an answering-plug in the jack of the calling-line. This restores the 50 annunciator in the way already described. She then grasps the remaining plug of the pair and tilts it toward her and receives the order, after which she has only to lift the plug already grasped, insert it in the jack of the 55 called subscriber, and press the calling-key. After the subscribers have rung off the withdrawal of the answering-plug again restores the annunciator.

It is also obvious that many of the details 60 herein described are applicable with advantage to multiple-switchboard exchanges.

I claim as my invention and desire to secure by Letters Patent—

1. In a telephone system, divided boards 65 and groups of subscribers' lines each group terminating in a board, trunk-lines terminating in plugs at both ends, for interconnecting the boards, said plugs being arranged in two sets at each board, the several trunk-lines from the plugs of the first set at one board 70 leading to plugs distributed in the second

sets of all the boards, substantially as described.

2. In a telephone system, divided boards, and groups of subscribers' lines each group 75 terminating in a board and trunk-lines interconnecting said boards, said trunk-lines divided into sets, each set terminating in answering-plugs at one board, and in calling-plugs distributed at all the other boards, whereby a connection may be originated on any one set of trunk-lines at one board only, substantially as described.

3. In a telephone system, divided boards, and groups of subscribers' lines, each group 80 terminating in a board, trunk-lines terminating in plugs at both ends for interconnecting the boards, said plugs being arranged in two sets at each board, the trunk-lines from plugs of the first set at one board leading to plugs 85 distributed in the second sets of all the boards, operator's circuit-terminals adjacent to the line-terminals on each board and means operated by the insertion of plugs of the first sets only to connect the subscribers' lines to 90 said operator's sets and the trunk-lines, whereby connections can be originated only by operators on the first sets, substantially as described.

4. In a telephone system, divided boards, 95 spring-jacks therein, and subscribers' lines connected thereto, operators' telephones at each board, trunk-lines divided into sets interconnecting the boards, means operated by the partial insertion of the terminal plugs of 100 a set at one board, to connect an operator's telephone to a subscriber's line or to the trunk-line or both, an independent switching means connected with the same set at all the boards to connect an operator's telephone 105 with any particular trunk-line of that set at said boards, substantially as described.

5. In a telephone system, divided boards, spring-jacks thereon, and subscribers' lines connected thereto, trunk-lines terminating 110 in plugs at both ends for interconnecting the boards, said plugs being arranged in two sets at each board, the trunk-lines from plugs of the first set at one board leading to plugs distributed in the second sets at all the boards, 115 an answering-operator's circuit-terminals adjacent to the line-terminals on each board and means operated by the partial insertion of plugs of the first sets only to connect the subscribers' lines to said answering-operator's telephone sets and the trunk-lines, a calling-operator's circuit-terminals adjacent to the plug-sockets of the second set of each board and means operated by tilting said plugs of the second sets to connect said calling-operator's telephones through the trunk-lines to the subscribers' lines, substantially as described.

6. In a telephone system, divided boards, 120 spring-jacks thereon, and subscribers' lines connected thereto, trunk-lines terminating 125 in plugs at both ends for interconnecting the

- boards, said plugs being arranged in two sets at each board, an answering and a calling-operator's telephone circuit-terminals at each board, means controlled by plugs of the first 5 set only for connecting subscribers' lines to said answering-operator's telephone and to the trunk-lines, and means controlled by plugs of the second set only for connecting said calling-operator's telephone through the 10 trunk-lines to subscribers' lines, a self-restoring annunciator having its actuating-coil connected to each subscriber's line and its restoring-coil connected to a terminal on the board, and means carried by all the plugs of 15 both sets for momentarily energizing said restoring-coil during the insertion or withdrawal of said plugs, substantially as described.
7. In a telephone system, divided boards 20 and subscribers' lines terminating in jacks therein, trunk-lines and plugs interconnecting the boards, and separate signaling-circuits also interconnecting the boards, means for energizing said signaling-circuits by the removal 25 of a trunk-plug from its socket, an operator's telephone connected to each board and means operated by the partial insertion of said plugs to connect the subscriber's line to the operator's set and to the trunk-circuit, substantially 30 as described.
8. In a telephone system, divided boards, and groups of subscribers' lines, each group terminating in a board, trunk-lines terminating in plugs at both ends for interconnecting 35 the boards, said plugs being arranged in two sets at each board, an answering and a calling operator's circuit-terminals at each board, an independent signaling-circuit for each trunk-line, means controlled by plugs of the 40 first set only for operating the signals in said signaling-circuits, and for connecting subscribers' lines to answering-operators' telephones and to the trunk-lines, and means controlled by plugs of the second set only for 45 operating return-signals in said signaling-circuits and for connecting said calling-operators' telephones through the trunk-lines to subscribers' lines, substantially as described.
9. In a telephone-switchboard, insulating 50 strips carrying rows of subscribers' terminals, a single operator's terminal carried upon and insulated from each row, and common to all the members thereof, plugs adapted to connect with any of the subscribers' terminals, 55 and alternate shoulders and depressions on said plugs, so proportioned that upon partial insertion thereof the subscribers' terminals will be forced into engagement with the operators' terminals, substantially as described.
10. In a telephone-switchboard, operators' 60 terminals; line-terminals underlying but normally out of contact therewith; a plug provided with insulated metallic portions adapted to make contact with said line-terminals 65 only, said metallic portions on the plug being each provided with an advance raised portion and a following depressed portion, said
- raised portion only having sufficient elevation to force the line-terminals into contact with the operators' terminals, substantially 70 as described.
11. A subscribers' metallic circuit; a line-terminal connected to each side thereof, an operator's metallic circuit and terminals connected to the respective sides thereof overlying the line-terminals; a plug provided with insulated metallic portions adapted to contact with the line-terminals only, said metallic portions on the plug being provided with advance annular shoulders and following annular depressions, said shoulders being so located and of such elevation as to simultaneously connect the operators' terminals with the line-terminals during the insertion or withdrawal of the plug, but not at its complete insertion or withdrawal substantially 85 as described.
12. In a telephone system, subscribers' lines terminating in spring-jacks, operators' telephone-circuit terminals and annunciator-restoring-circuit terminals adjacent to the line-springs in each jack, answering and calling plugs connected in pairs by cord-circuits, means carried by both plugs of a pair to actuate the annunciator-restoring terminals, 90 and means carried by the answering-plugs only to actuate the operators' telephone-terminals, substantially as described.
13. In a telephone-switchboard subscribers' lines terminating in jacks thereon, an annunciator for each line, plugs and plug-circuits for interconnecting said lines, an operator's telephone and means whereby the partial insertion of one of said plugs in, or its partial withdrawal from a jack restores the annunciator and at the same time connects the operator's telephone to the line, substantially as 100 described.
14. In a telephone system, a subscriber's line and terminals therefor, a signal and signal-operating means under control of said line, a plug, and signal-restoring means energized momentarily at a certain point during the insertion or withdrawal of the plug, whereby while the plug is fully inserted or withdrawn 105 the signal will remain under control of the line substantially as described.
15. In a telephone system, a switchboard, terminals thereon, subscribers' lines connected thereto, self-restoring annunciators normally under the control of, and plugs for interconnecting said subscribers' lines, and means energized at one point during the insertion or withdrawal of the plugs for momentarily removing the annunciator from the control of the subscribers' lines, by restoring the same and thereafter leaving the restored annunciators again under control of the subscribers' lines, substantially as described.
16. In a telephone-switchboard, spring-jacks thereon, and subscribers' lines connected thereto, self-restoring annunciators having their actuating-coils connected to their respective lines, springs connected to the re-

storing-coils and arranged in juxtaposition to but insulated from the line-spring of the jacks, and connecting-plugs each provided with one or more annular depressions and alternate elevations so located as to close the restoring-circuit momentarily during the insertion or withdrawal of a plug and thereafter leave the annunciator under the control of the line, substantially as described.

17. In a telephone system, a subscriber's line terminating at a switchboard, a signal and operating means therefor connected to said line, a signal-restoring means also connected to said line and to a terminal on the board, an operator's set also connected to said terminal, a plug, and means whereby on the partial insertion or withdrawal of said plug the signal is restored and the operator's set connected to the line, substantially as described.

18. In a telephone-switchboard a terminal plug and its seat, an operator's telephone circuit and terminals therefor adjacent to said seat, and the arrangement being such that the tilting of said plug in its seat connects said terminals to the plug-circuit, substantially as described.

19. In a telephone-switchboard a plug and seat therefor recessed on one side, operator's telephone-circuit terminals adjacent thereto, contact-springs coöperating with said terminals and connected to the plug-circuit, and intermediate means whereby the tilting of the plug in its socket will close said contact-springs upon said terminals, substantially as described.

20. In a telephone-switchboard a plug-seat having a metallic portion, a contact-spring in juxtaposition thereto, a signaling-circuit including the metallic portion and said contact-spring, and a plug having a metallic heel adapted to bridge across said seat and spring and so complete the signaling-circuit, an operator's telephone-circuit terminals, a switch therefor with connections to the plug-circuit, and means whereby the tilting of said plug in its seat will actuate said switch to connect the operator's telephone into the plug-circuit without altering the condition of the signaling-circuit, substantially as described.

21. In a telephone-switchboard a metallic plug-seat, a contact-spring adjacent thereto, a signaling-circuit including said seat and spring, and a plug having a metallic heel adapted to bridge across the same, an oper-

ator's telephone-circuit terminals, a switch therefor connected to the plug-circuit and an insulated mechanical connection between said switch and the aforesaid contact-spring, said mechanical connection carrying a projection whereby either the tilting of the plug in its seat or the retraction of the projection after the plug is removed will operate through the medium of the contact-spring to actuate the telephone-switch, substantially as described.

22. A signaling-circuit, high and low resistance signals therein, said circuit being normally open at the low-resistance signal, a circuit-breaker and a resistance in shunt therewith adjacent to the high-resistance signal to energize both signals, and means for operating the circuit-breaker adjacent to the high-resistance signal, to increase the resistance of the circuit, and thereby deenergize the low-resistance signal, substantially as described.

23. In a signaling system a source of current, a low-resistance signal, a normally-open circuit-breaker adjacent thereto a high-resistance signal and a normally-closed circuit-breaker adjacent thereto; said source of current, signals and circuit-breakers being contained in series in a single circuit, and a resistance shunting said normally-closed circuit-breaker, the resistance of the shunt-circuit and that of the signals being so adjusted that the high-resistance signal will be displayed whenever the normally-open circuit-breaker is closed, and the low-resistance signal will be displayed only when both circuit-breakers are closed, substantially as described.

24. In a signaling system a circuit containing a low-resistance signal, a normally-open circuit-breaker adjacent thereto, a high-resistance signal, a normally-closed circuit-breaker adjacent thereto, and a source of current; a resistance shunting said normally-closed circuit-breaker, said resistance and the resistance of the signals being so adjusted that the high-resistance signal is displayed on the closure of the normally-open circuit-breaker, and is unaffected by the condition of the normally-closed circuit-breaker, while the low-resistance signal is displayed only when both circuit-breakers are closed, substantially as described.
